US00D603674S

(12) **United States Design Patent**
Werner

(10) **Patent No.:** **US D603,674 S**
(45) **Date of Patent:** **** Nov. 10, 2009**

(54) **HAMMER DRILL**

(75) Inventor: **Immanuel Werner**, St. Johann (DE)

(73) Assignee: **Robert Bosch GmbH**, Stuttgart (DE)

(**) Term: **14 Years**

(21) Appl. No.: **29/334,804**

(22) Filed: **Apr. 2, 2009**

(30) **Foreign Application Priority Data**

Feb. 11, 2009 (EM) 001086755

(51) **LOC (9) Cl.** **08-02**

(52) **U.S. Cl.** **D8/67**

(58) **Field of Classification Search** D8/61-70;
81/57.11, 54, 57.42; 173/170, 271; 74/55

See application file for complete search history.
